UNITED STATES PATENT OFFICE.

JOHN F. CARPMILL, OF NEW BRITAIN, CONNECTICUT.

AUTOMOBILE HOOD FASTENER.

Application filed October 5, 1922. Serial No. 592,556.

To all whom it may concern:

Be it known that I, JOHN F. CARPMILL, a citizen of the United States, residing at New Britain, in the county of Hartford and State 5 of Connecticut, have invented certain new and useful Improvements in Automobile Hood Fasteners, of which the following is a specification.

This invention relates to an automobile 10 hood fastener and among the objects of the invention are the provision of an article of this character which is simple in construction and highly efficient in pulling the hood over the engine down tight and at the same 15 time putting a pressure against the side of the hood so as to eliminate or reduce as far as possible rattle.

In the drawing accompanying and forming part of the present specification, I have 20 shown in detail a form of embodiment of the invention which to enable those skilled in the art to practice the same will be set forth fully in the following description. Obviously I am not restricted to this disclosure. 25 I may depart therefrom in a number of respects within the scope of the invention defined by the claims following said description.

Referring to said drawing:

30 Fig. 1 is an elevation as seen for instance from the rear, of a hold-down device involving the invention.

Fig. 2 is an elevation as seen from the right in Fig. 1.

35 Fig. 3 is a section on the line 3—3 of Fig. 2.

In the figures of the drawing I have shown a part of the front portion of the chassis 2 of an automobile. The chassis at 40 its forward portion sustains a motor or engine which I have not represented because it forms no part of the invention.

The engine is covered by a hood 3, the sides 4 of which practically generally duplicates of each other are pivoted to the body of the hood in the ordinary fashion so that either side 4 can be swung up to obtain access to the engine when required. These sides 4 are in action, subjected to considerable vibration and this causes objectionable noises, and the primary purpose I have in view is to eliminate as far as possible these noises. As a matter of fact in my copending application Ser. No. 592,555 filed October 5, 1922, I show a structure where I have in view the same general motives.

The sides 4 are normally held down by one or more holding down members such as those denoted in a general way by 5. In practice there are generally two of these holding 60 down members associated with each of the sides. The holding down member 5 shown involves a tubular body 6 which incloses a piston 7 having what is shown at its upper end, the head 8. The piston rod 7 is as 65 shown surrounded by a coiled spring 9, the upper end of which bears against the head while the lower end bears against the lower end of the tubular body 6 through which the piston rod 7 extends. The spring, therefore, acts constantly to longitudinally separate the two main elements of the holding down member 5. As shown, the rod 7 extends through an opening 10 in the top of the semi-spherical piece 11 which is attached rigidly to the chassis 2 in some proper manner. The rod has at its lower end a foot 12, to prevent the rod from being pulled from the semi-spherical body 11 although the rod 7 is free to swivel or in fact move 70 universally.

The upper end of the tubular body 6 is closed by the cap 13 which may be driven or otherwise closely fitted onto the tubular body so as to close the upper end thereof. 85 The cap 13 may have on its upper side the third portion 14 to facilitate its movement when required. In addition to this, it may have the lateral finger pieces 15 by which the sleeve or tube 6 can be when required 90 lifted. The element 5 in addition to applying a holding-down effect to the side 4 of the hood 3, also applies a lateral pressure thereto as I will hereinafter explain.

The side 4 may have at a proper height 95 the keeper or catch member 17 cooperative as shown, with the hook 18 on the upper end of the shank 19, the shank having fastened thereto as by the pin 20, the pad 21 usually of rubber and which is intended to bear against the outer surface of the side 4.

The shank 19 has on its rear side an upper portion, the lug 22 on which is flexibly mounted as by pivoting at 23 between the ears 24 which extend outwardly from the 105 head 13. In view of the construction described, the automobile hood side 4 is not only held down by a firm, substantial pull, but an equally firm side thrust is applied to it so as to effectually prevent motion of the 110 same when the car equipped with the structure is in motion.

What I claim is:

1. In a device of the class described, the combination of a hold-down member, a catch member to be attached to the side of an automobile hood, and a shank pivotally connected to the hold-down member, having a soft pad to engage the side of said hood.
2. In a device of the class described, the combination of a tube, a cap closing the upper end of the tube, a piston rod in the tube, extending from the lower end thereof and having a head in the tube, a spring around the piston rod, bearing against said head

and also against the lower end of the tube, means for loosely mounting the piston rod for universal movement, a shank pivotally connected to said cap, for engaging a catch member, the shank having a soft pad on its interior portion to engage the side of an automobile hood.

In testimony whereof I hereby affix my signature.

JOHN F. CARPMILL.
